UNITED STATES PATENT OFFICE.

HARRY DONALD McDONALD, OF LOS ANGELES, CALIFORNIA, ASSIGNOR OF ONE-FOURTH TO JOHN E. STALEY, ONE-FOURTH TO H. L. BROWN, AND ONE-FOURTH TO MAUDE C. McDONALD, ALL OF LOS ANGELES, CALIFORNIA.

DESIGN FOR A CIGAR LIGHTER OR SIMILAR ARTICLE.

Application filed April 7, 1925. Serial No. 13,044. Term of patent 3½ years.

To all whom it may concern:

Be it known that I, HARRY DONALD McDONALD, a citizen of the United States, residing at Los Angeles, in the county of Los Angeles and State of California, have invented a new, original, and ornamental Design for Cigar Lighters or Similar Articles, of which the following is a specification, reference being had to the accompanying drawing, forming part hereof.

The drawing is a perspective view showing my new design for cigar lighters or similar articles.

I claim:

The ornamental design for a cigar lighter or similar article, as shown.

HARRY DONALD McDONALD.

Witnesses:

JOHN E. STALEY,
J. CALVIN BROWN.
